UNITED STATES PATENT OFFICE.

DAVID D. GORDON, OF CHICAGO, ILLINOIS, ASSIGNOR TO THE YOST ELECTRIC MANUFACTURING COMPANY, OF TOLEDO, OHIO, A CORPORATION OF OHIO.

ELECTRIC-SWITCH MECHANISM.

1,228,907.

Specification of Letters Patent.

Patented June 5, 1917.

Application filed November 21, 1916. Serial No. 132,604.

To all whom it may concern:

Be it known that I, DAVID D. GORDON, a citizen of the United States, and a resident of Chicago, in the county of Cook and State 5 of Illinois, have invented a certain new and useful Electric-Switch Mechanism; and I do hereby declare the following to be a full, clear, and exact description of the invention, such as will enable others skilled in the art 10 to which it appertains to make and use the same, reference being had to the accompanying drawings, and to the characters of reference marked thereon, which form a part of this specification.

15 This invention relates to electric switches, and particularly to those of the key controlled snap-switch type.

The object of my invention is the provision of an improved switch of this character, 20 which is simple, strong and durable in its construction, is capable of being easily and quickly assembled, and is admirably adapted for use in electric lamp sockets. Other objects and advantages of the invention will 25 be apparent from the following detailed description thereof.

While the invention, in its broader aspect, is capable of embodiment in numerous forms, a preferred embodiment thereof, with 30 two separate means of mounting the same in an electric socket, is illustrated in the accompanying drawings, in which—

Figure 1 is a central longitudinal section of an electric socket embodying the invention, with a part in full, and with the switch shown in open position. Fig. 2 is an inner or upper end view of the socket with the top members of the insulating body and shell removed. Fig. 3 is a side elevation of the 40 socket with the shell removed and with a portion of the screw shell broken away. Fig. 4 is a view of the plug receiving end of the socket. Fig. 5 is a perspective view of the insulating body of a socket with the screw shell removed. Fig. 6 is a perspective view of the bridging member of the switch, and Fig. 7 is a central longitudinal section of a socket embodying the invention with the shell removed therefrom and illustrating a modified form of mounting the key shaft therein.

Referring to the drawings, 1 and 2 designate the base and top members of the insulating body of an electric socket, which members are mounted one on top of the other

and secured in such position in any suitable or convenient manner, and coöperate to form a chamber 3 for receiving the switch mechanism. The switch body, in the present instance, is shown as being mounted in the customary shell, which comprises separably connected base and cap sections 4 and 5, respectively. 6 designates an insulating lining which is disposed between the base member 1 of the shell and the insulating body, and also between said shell member and the screw shell 7, forming the socket into which a plug or other attaching member is inserted. The screw shell 7 is secured to the outer end of the base member 1 of the insulating body, in the present instance by screws 8, 8, which also secure a segmental conductor plate 9 to the inner end of the screw shell in electrical conductive connection therewith. The plate 9 has a finger 10 projecting upward therefrom into a registering recess 11 in the insulating section 1, and carries a terminal binding screw 12 in said recess. A surface groove 13 extends from the recess 11 longitudinally of the insulating body to the upper end thereof to permit the extending of a terminal wire to the binding screw 12 between the insulating body and the insulating sleeve 6 from the wire receiving end of the inclosing shell.

The center contact 14 of the socket is secured to the outer end of the insulating section 1 by a screw 15, and has its arm extended around one edge of the insulating member 1 and up to exposed position within one side of the switch receiving chamber 3, where it forms a contact 16 disposed within the chamber 3 at one side thereof. In spaced relation to the contact 16 is a second contact finger 17 which extends around the lower edge of the insulating block 1, being secured, in the present instance, to the under side thereof by a screw 18, and thence extending into a recess 19 in one side of the insulating section 1. A terminal binding screw 20 is secured to the conductor finger 17 within the recess 19, and a terminal wire is led thereto through a surface recess or screw 21 provided longitudinally in one side of the insulating body.

Mounted within the chamber 3 of the insulating body is a frame 22 which is secured to the base section of said body by a screw 23 and has the guide standard 24

rising from one end thereof substantially midway of the two contacts 16 and 17 and in spaced relation thereto, as shown. The opposite or inner end portion of the frame 22 is provided with the upstanding legs or standards 25 and 26, which coöperate to form bearings for a key shaft 27, which projects transversely of the insulating body and outward from the chamber 3 therein through an opening 28, which is provided between the adjacent faces of the insulating blocks 1 and 2, and in transversely opposed relation to the side portion of the insulating body in which the contacts 16 and 17 are disposed. The key shaft 27 is provided at its outer end with the customary thumb piece 29. For convenience in assembling, the shaft receiving openings in the upper or free ends of the bearing standards 25 and 26 are in the form of notches extending from the outer ends of said standards and have the outer end portions of their side walls inwardly compressed to rotatably retain the shaft therein. The shaft 27 is provided at its inner end with a crank arm 30, which is disposed between the frame standards 24 and 25 in spaced relation to the former.

The frame standard 24, which is disposed substantially intermediate the contacts 16 and 17, forms a guide for directing the reciprocatory contact making and breaking movements of a bridging piece 31, which is adapted to slidably rest or bear outward against the inner side of said standard with its opposite ends extending transversely from the standard in position to have sliding contact with the respective contacts 16 and 17 when moved into circuit closing position at the inner end of the guide standard. The bridging piece has its body portion provided with outwardly projecting spurs or fingers 32 adjacent to its upper and lower edges and at opposite edges of the guide standard for coöperating with said standard edges to guide the reciprocatory movements of the bridging piece. In other words, the bridging piece which I preferably employ comprises a body portion of U-form for fitting over the inner side of the guide standard 24 and has contact fingers projecting in opposite directions therefrom in position to make contact with the respective contacts 16 and 17 when moved into position for such purpose. The bridging piece 31 has its movements limited at one end by contact with the frame 22 and at its other end by the contact of its upper spurs 32, with spurs or projections 33 provided at the upper end of the standard 24 at the respective edges thereof (Fig. 5).

The bridging piece 31 is yieldingly held in sliding engagement with the guide standard 24 by a coiled compression spring 34, which has one end in outward thrust con-

tact with the inner side of said bridging piece in opposition to said frame standard, in engagement with a centrally disposed stud 35 thereon, which is received within the end of the spring. The other end of the spring is in thrust contact with the wrist pin portion of the crank arm 30, with the wrist pin of such arm projecting into the spring end. The throw of the crank wrist pin when revolved is greater than the permissible reciprocatory movement of the bridging piece 31, so that the crank 25 and spring 34 will coöperate to effect snap-switch movements of the bridging piece, first in one direction and then the other, upon a turning of the shaft 27 in either direction, a shifting movement being imparted to the bridging piece at each half revolution of the crank, as is apparent.

The spring 34, in addition to holding the bridging piece 31 in sliding engagement with the frame standard 24 and imparting snap-switch movements to the bridging piece when the key shaft is turned, also cooperates to yieldingly hold the ends or side arms of the bridging piece in contact with the stationary contacts 16 and 17 when the bridging piece is in position therefor. In other words, the spring permits an inward movement of the bridging piece as it moves into contact with the contacts 16 and 17, such movement being sufficient to compensate for wear, thus insuring the making of a perfect contact between the circuit closing parts when the bridging piece is in position therefor.

It is evident that my switch mechanism is capable of being easily and quickly assembled as it is only necessary to place the bridging piece 31 in sliding engagement with the inner side of the guide standard 24 and to dispose the spring 34 between the bridging piece and crank arm in engagement with each, thus enabling either a new bridging piece, or spring, or both, to be quickly substituted for old parts should they become broken or unfit for use from any cause.

In the modification shown in Fig. 7 the switch construction is the same as that above described, except that instead of mounting the key shaft in the bearing standards 25 and 26 it is mounted in bearings provided between the adjacent faces of the insulating members 1 and 2. In this construction the outward spring actuated thrust of the shaft is opposed by a collar 36 on the shaft bearing outward against a thrust part 37 provided in the insulating body. In this construction the frame from which the guide standard 24 projects is designated 38.

I wish it understood that my invention is not limited to any specific construction, arrangement or form of the parts, as it is capable of numerous modifications without departing from the spirit of the claims.

Having thus described my invention, what I claim as new, and desire to secure by Letters Patent, is—

1. In a switch of the class described, a pair of spaced contacts, a guide standard disposed adjacent to and between said contacts, a bridging piece slidably bearing against a side of said standard and having spurs extending around the respective side edges of the standard in guiding engagement therewith and having parts at opposite edges of the standard for contact with respective of said spaced contacts when the bridging piece is at one end of its movement, a shaft mounted transversely of said standard and having a crank arm at one end adjacent to said standard, and a coiled compression spring interposed between said bridging piece and crank arm in engagement with each and operable to impart snap switch movements first in one direction and then the other to the bridging piece when the shaft is turned.

2. In an electrical connecting member, a pair of spaced contacts, a guide disposed between said contacts, a bridging piece guided for circuit making and breaking movements by said guide, said bridging piece comprising a body part having spurs projecting transversely therefrom for engagement with said guide to prevent transverse movements of the bridging piece relative thereto and having arms projecting from opposite side edges in position to make contact with respective of said stationary contacts when the bridging piece is in one position of its movement, and means having a revolute member and a coiled compression spring connecting said revolute member and bridging piece and operable to impart successive snap shifting movements to said bridging piece to move it into and out of circuit bridging position.

In testimony whereof, I have hereunto signed my name to this specification.

DAVID D. GORDON.
